UNITED STATES PATENT OFFICE.

ALBERT Y. FRY, OF GALLATIN, TENNESSEE.

GATE.

No. 825,716.

Specification of Letters Patent.

Patented July 10, 1906.

Application filed February 15, 1906. Serial No. 301,172.

To all whom it may concern:

Be it known that I, ALBERT Y. FRY, a citizen of the United States of America, residing at Gallatin, in the county of Sumner and 5 State of Tennessee, have invented certain new and useful Improvements in Gates, of which the following is a specification, reference being had therein to the accompanying drawings.

10 This invention relates to certain new and useful improvements in gates; and the invention has for its primary object the provision of novel means for opening and closing a gate when approaching the same from either side.

15 The invention aims to provide a gate particularly adapted for country roads and lanes, and in this connection I have devised novel means for opening and closing a gate to permit a vehicle to pass therethrough 20 without necessitating a person leaving the vehicle to open and close the gate. To this end I have constructed a simple and inexpensive gate of the character above described which can be easily and quickly manipulated 25 at any time it is desired to open and close the gate.

With the above and other objects in view, which will more readily appear as the nature of the invention is better understood, the 30 same consists in the novel construction, combination, and arrangement of parts to be hereinafter more fully described and claimed, and, referring to the drawings accompanying this application, like numerals of reference 35 designate corresponding parts throughout both views, in which—

Figure 1 is a plan of my improved gate; and Fig. 2 is a side elevation, partly in section, of the gate in an open position.

40 In constructing my improved gate I erect four posts or standards 1, 2, 3, and 4 at one side of the road or lane in connection with which my improved gate is to be used. In the accompanying drawings I have illustrated these posts or standards as being supported by a longitudinally-disposed beam or girder 5; but it will be observed that this beam or girder may be dispensed with and the posts or standards planted in the ground.

45 Upon the opposite side of the road or lane, diametrically opposite the post or standard 3, is erected another post or standard 6, herein-after termed a "locking-post." The post 3 and the post 6 have been illustrated as connected by a transverse beam or girder 7, the 55 use of this beam or girder being arbitrary.

A gate 8 is connected to the post 3, as at 9 9, said gate consisting of a plurality of parallel rails 10, vertically-disposed rails 11, and diagonally-disposed rails 12, all of said rails 60 being suitably secured together to form a strong and durable gate-frame. The uppermost rail 10 of the gate adjacent to the post 3 is provided with an angle-arm 14, extending over the top of the post 3. Pivoted to the 65 outer end of the arm 14 is a lever 15, having its ends provided with apertures 16 and 17, the object of which will be presently described.

The gate is provided with a latch-bar 18, 70 said bar being slidably mounted upon one of the parallel rails 10 between the vertical rails 11 11 at the end of the gate. The latch-bar is provided with two outwardly-extending pins 19 19, which limit the rearward 75 movement of the latch, also with pins 20 20, that limit the forward movement of the latch, said pins being adapted to impinge against the vertical rails 11 11 of the gate. The lowermost parallel rail 10 of the gate is 80 provided with upwardly-extending resilient arms 21 21, adapted to engage behind the pins 20 20 and normally hold the latch in an extended position. The upper ends of the 85 posts or standards 1 and 4 are provided with brackets 22 22, between which are journaled rollers 23 and 24, having crank-handles 25 25. The upper end and one side of the post 2 are provided with guide-eyelets 26 and 27. The endless cord or cable 28 is used 90 in connection with the rollers 23 and 24, said cord or cable being wound around the rollers and extending from one roller to the other, thus forming two strands 29 and 30, the strand 29 being connected to the lever 15 95 through the medium of the aperture 17, this strand also passing through the eyelet 26 of the post or standard 2. The strand 30 passes from one roller to the other and in so doing passes through the eyelet 26, carried by 100 the upper end of the post 2. The cable or cord 31 is connected to the rear end of the latch-bar 18 and to the lever 15 through the medium of the aperture 16. The locking-post 6 and the post 2 are provided with 105 keepers 32 32, adapted to be engaged by the end of the latch-bar 18 when the gate is either closed or opened.

In practice the posts or standards 1, 2, and 4 will be located a sufficient distance away 110 from the gate to permit of a vehicle approaching either the post 1 or 4, whereby the

roller 23 or 24 may be operated to open or close the gate.

In Fig. 1 of the drawings I have illustrated the gate in a closed position, and in describing the operation of the gate I will assume that the gate is to be opened. The crank-handle 25 of the roller 23 is rotated, which winds the strand 30 upon the roller 23 and winds the strand 29 upon the roller 24, the winding of said strand upon the roller 24 pulling rearwardly upon the lever 15, which withdraws the latch-bar 18 from the keeper 28 of the locking-post 6, and a further movement of the strand 29 in the direction of the roller 24 swings the gate 8 open, this being accomplished through the medium of the angle-arm 14. When the gate engages the post 2, the slack cable 31 permits of the resilient arms 21 21 forcing the latch-bar 18 into engagement with the keeper 32 of the post 2. Upon the vehicle passing between the posts 3 and 6 the crank-handle of the roller 24 is rotated, which winds the strand 30 upon said roller and the strand 29 upon the roller 23. When the strand 29 is pulled forwardly, the gate is swung to a closed position through the medium of the angle-arm 14, and the slack in the cable 31 permits of the latch-bar 18 engaging the keeper of the locking-post 6. From the foregoing it will be observed that I have devised a simple and inexpensive mechanism for opening and closing a gate such as would be used upon country roads, lanes, or a farm, where persons riding in a vehicle are put to considerable trouble in leaving the vehicle to open a gate, then driving through, and then returning to close

the gate. My invention obviates the necessity of a person leaving the vehicle, it only being necessary to stop adjacent to the post 1 of the gate, then passing through the same and stopping at the post 4 to close the gate.

I do not care to confine myself to the character of gate in connection with which my improved mechanism is used, and such changes in the construction and operation of the gate as are permissible by the appended claim may be resorted to without departing from the spirit and scope of the invention.

What I claim, and desire to secure by Letters Patent, is—

In a gate the combination with four posts arranged in alinement and a fifth post arranged laterally of the alined posts, of a gate hinged to one of the alined posts, keepers carried by another of the alined posts and by the laterally-arranged post, a spring-held latch carried by the gate, an angle-arm carried by the gate and extending over the post to which the gate is hinged, a roller carried by each of the end posts of said alined posts, an endless cable wound around both said rollers, a lever pivotally attached at its center to said angle-arm and having one end attached to one strand of said cable, a cord attached to the other end of said lever and attached at its opposite end to said latch, and crank-handles carried by said rollers.

In testimony whereof I affix my signature in the presence of two witnesses.

ALBERT Y. FRY.
